(57) **CLAIM**

The ornamental design for a surveillance camera as shown and described.

DESCRIPTION

FIG. 1 is a front, bottom perspective view of a surveillance camera, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The even dashed broken lines shown in the drawings are included for the purpose of illustrating portions of the surveillance camera that form no part of the claimed design. The dot-dash broken lines immediately adjacent to the claimed areas in the views represent the boundaries of the design and form no part thereof.
